UNITED STATES PATENT OFFICE.

WILLIAM C. HEATH, OF BELOIT, WISCONSIN, ASSIGNOR TO FAIRBANKS, MORSE & CO.,
OF CHICAGO, ILLINOIS, A CORPORATION OF ILLINOIS.

PROTECTED ELECTRODE IGNITER.

Application filed January 14, 1921. Serial No. 437,340.

To all whom it may concern:

Be it known that I, WILLIAM C. HEATH, a citizen of the United States, residing at Beloit, in the county of Rock and State of Wisconsin, have invented a certain new and useful Improvement in Protected Electrode Igniters, of which the following is a specification.

This invention relates to the class of igniters used in internal combustion engines employing oil as fuel in which one of two electrodes located in the firing compartment of the engine is moved into and out of contact with the other to produce a low tension spark for firing the fuel charge.

The object is to provide a mechanism of this class with protection for the contact points of the electrodes as they operate thereby greatly increasing the efficiency of the firing mechanism by preventing the dissipation of heat at the contact points and by excluding, in large degree, direct contact of fuel oil with the contact points.

The invention consists in means for carrying out the foregoing and other objects which can be easily and cheaply made, which is satisfactory in operation and not readily liable to get out of order. More particularly the invention consists in detail of construction more fully set forth in the specification and claims.

Referring to the drawings in which similar numerals represent the same parts throughout the several views,

Figure 1 is an end view of the exterior of an igniter plug carrying mechanism illustrating this invention in its preferred form as applied to an engine cylinder, certain wall portions being broken away to show the interior construction.

Figure 2 is a sectional plan view taken on the line 2—2 of Figure 1.

Figure 3 is an end detail view on the line 3—3, Figure 2.

Figure 4 is a modified construction of the essential parts of Figure 2.

For the purposes of illustration the essential parts of mechanism of this invention are shown as applied to the conventional form of an igniter body block 10 detachably inserted in the end wall 12 of an engine cylinder 14, the outer end of this block being covered by the usual removable cover 16, and the whole secured in place by lag screw 17.

In the preferred form of structure shown in

Figure 2 the block 10 has projecting from its inner or engine end a relatively small cylindrical cup or chamber 18 having its end 20 open into the engine cylinder so that fumes of combustible material to be fired can enter the cup. Extending thru the block 10 and cup 18 is a stationary electrode 22 of conventional construction insulated from the material of the block 10 by a sleeve 24 and a nut 26. The outer end of this electrode is equipped with the usual electric wire connections 28 leading to a distant magneto (not shown.) The inner end of this electrode 22 extends partway into the interior of cup 18, being insulated from its walls by an air space as clearly shown in Figure 2, and carries a stationary firing contact 30.

Journalized in block 10 at a suitable distance from the electrode 22 is a rotatable electrode 32 not here insulated from the block 10. The outer end of this electrode 32 carries a crank arm 34 rocked in any suitable manner as by reciprocating rod 36 driven by the engine and resisted by the spring 37.

The inner end of electrode 32 carries inside the engine cylinder a lever arm 38 having at its outer end a curved portion 40 terminating in the contact point 42, lying in the arc of a circle drawn about the center of rotation of the electrode member 32 so that as the electrode 32 is rocked these two parts reciprocate thru a perforation 44 in the top of member 18 to cause contact 42 to engage contact 30 on electrode 22. This perforation is made only large enough to permit ready movement as described.

The alternative form of construction shown in Figure 4 differs from that of Figure 2 only in that the tubular cup 46, corresponding in all operative functions to the cup 18 is carried by the insulating sleeve 48 corresponding to sleeve 24. The construction and mounting of protecting cups 18 and 46 is wholly immaterial. The point is that the cup provided protects the firing contacts 30 and 42.

In the operation of the device fuel oil is thrown into the combustion space of the engine by mechanism not entering into this invention and therefore not shown in detail and fumes from it pass thru openings 20 and 44 into proximity with the contacts 40—42 and are fired by the spark produced in the ordinary manner as the contacts separate in moving from the position of Figure 1

- to that of Figure 3. When firing takes place intense heat is produced within the chamber 18 or 46 immediately adjacent to the contact members 30—42. The presence of the 5 protecting case serves the purpose of retaining a large quantity of this heat immediately adjacent to the contacts 30—42 during the time between successive firings—therefore it enables the firing to take place more 10 surely and efficiently than is the case where the contacts are allowed to be cooled in any manner whatever as for instance by being struck by a spray of cold oil during the intervening time.
- 15 The presence of the protecting case 18 or 46 also serves the purpose of keeping the oil spray normally supplied to the engine cylinder off from the contact points 30—42 thereby reducing if not preventing the usual 20 forming of carbon on these points. Stated in another way, the advantage is that there will be less formation of carbon around the spark points under conditions where this carbon is otherwise likely to form. The 25 action of the protection sleeve tube seems to be in keeping the liquid particles of fuel which may form carbon, away from the points and also to produce a somewhat higher heat effect around the points, resulting in the burning off of such carbon as may 30 otherwise form.
- Having thus described my invention what I claim as new and desire to secure by Letters Patent is:—
- 35 1. In an igniter mechanism two electrodes carrying engageable contact points, rotatable means moving one electrode to engage and separate said contact points, and tubular enclosing member entered by one electrode 40 at its end and by the other electrode at its side substantially enclosing the points as they engage each other.
2. In mechanism of the class described, a base plug for insertion in an opening in an 45 engine combustion chamber wall, a cup protruding from the inside of the plug, an electrode thru the plug entering the bottom of said cup, another electrode rotatable in the plug parallel with the first electrode, and 50 an arm on the inner end of the rotatable electrode, movable between two positions in one of which it enters an opening in the

cup and contacts the electrode therein and in the other of which it does not so contact.

3. In mechanism of the class described, a 55 base plug for insertion in an opening in an engine combustion chamber wall, a cup protruding from the inside of the plug, an electrode thru the plug entering the bottom of said cup, another electrode rotatable in the 60 plug parallel with the first electrode, and an arm on the inner end of the rotatable electrode movable between two positions in one of which it enters an opening in the cup and contacts the electrode therein and in 65 the other of which it does not so contact, and means for rotating the second electrode.

4. In mechanism of the class described a 70 base plug for insertion in an opening in an engine combustion chamber, a cup protruding from the inside of the plug, an electrode thru the plug entering the bottom of said cup, another electrode rotatable in the plug 75 parallel with the first electrode and an arm on the inner end of the rotatable electrode 80 movable between two positions in one of which it enters an opening in the cup and contacts the electrode therein, and in the other of which it does not so contact, means for rotating the second electrode, and means 85 for insulating one of said electrodes from the base plug.

5. In mechanism of the class described, a plate for securement to an opening in an engine wall, a tubular cup open at its end 85 protruding from the plate into the engine, a stationary contact point in the cup opposite another opening in a side wall of the cup, another electrode outside the cup, movable to carry a contact thru said second 90 opening in the cup, and means moving the second electrode to cause the second contact to engage and disengage the first, and means insulating the electrodes when the contact points do not engage, for the purposes set 95 forth.

In witness whereof, I have hereunto subscribed my name in the presence of two witnesses.

WILLIAM C. HEATH.
